UNITED STATES PATENT OFFICE.

THOMAS ALBERT CROMPTON, JR., AND FRANK CROMPTON, OF LONDON, ENGLAND.

STEAMING APPARATUS FOR PETROL-TANKS AND THE LIKE.

1,245,878.

Specification of Letters Patent.

Patented Nov. 6, 1917.

Application filed May 15, 1917. Serial No. 168,681.

To all whom it may concern:

Be it known that we, THOMAS ALBERT CROMPTON, Jr., and FRANK CROMPTON, both subjects of the King of England, and residents of Limehouse, London, E., England, have invented certain new and useful Improvements in Steaming Apparatus for Petrol-Tanks and the like, of which the following is a specification.

10 This invention is for improvements in or relating to steaming apparatus for petrol-tanks and the like and has for its object to provide a new form of apparatus of the type employed for receptacles for inflammable fluid, which apparatus ordinarily comprises a ventilating-shaft provided with a steam-admission conduit in addition to the said ventilating-conduit with its usual double-acting relief-valve, the said steam-admission 15 conduit being controlled by a valve which, when the steam is admitted, is raised to shut off the relief-valve, but at other times operates to close the steam-admission conduit. Apparatus of this type is used for steaming 20 out the container when empty or for admitting steam to extinguish fire if this should occur within the container.

It is well-known that tank steamers and other containers for petrol for example, require ventilation. For this purpose a conduit is usually provided which communicates with the upper portion of the tank and has at its top a double-acting valve which will allow the escape of gas if pressure is set 25 up within the container or will allow air to enter if the pressure in the container is lowered either by the withdrawal of liquid or by other means, and the apparatus already referred to is applied to this ventilating, 30 conduit so that steam may be discharged into the container by means of the same conduit without interfering with the said double-acting relief-valve, a further valve being provided to automatically shut off communication 35 with the relief-valve as already described when steam is admitted by the communicating-conduit provided therefor.

One object of the present invention is to so arrange this second valve that when it is 40 moved by the steam to shut off the relief-valve, there will be little or no tendency to displace it from the position into which it is thus moved.

According to this invention, apparatus for 45 steaming petrol-tanks or the like comprises the combination with a ventilator-conduit

controlled at one end by a double-acting relief-valve, of an injector-conduit which enters a part of the ventilator-conduit controlled by the said valve, has its delivery-end within the ventilator-conduit and directed away from the valve, and has a movable wall-portion whose exterior is shaped to coöperate with a seating in the ventilator-conduit as a valve to shut off the said relief-valve when fluid under pressure is admitted to the injector-conduit, so that when steam for example, is admitted for cleaning purposes, the pressure of the steam upon this wall-portion will cause it to shut off the relief-valve, and the steam being driven forward from the injector-conduit will have little tendency to pass back in the opposite direction to create pressure in a direction tending to unseat the valve provided by the 55 said wall-portion.

Preferably, the injector-conduit is provided with an elbow within the ventilator-conduit at the point where it enters the latter, and the movable wall-portion is situated 60 on a face of the elbow which is toward the relief-valve, so that a seating for this movable wall-portion can be readily accommodated within the area of the ventilator-conduit, the movable wall-portion being conveniently mounted concentrically with that 65 part of the ventilator-conduit which contains the relief-valve and is to be shut off. The movable wall-portion is conveniently in the form of a valve alined to coöperate with 70 a seating formed for it in the ventilator-conduit, and has attached to it a shroud which lies within the injector-conduit, so that when the valve is moved out under pressure of 75 fluid admitted to the injector-conduit, the shroud seals the conduit-opening wherein 80 the valve moves.

In the accompanying drawing which illustrates one method of carrying out this invention, as much of the apparatus is shown 85 as is necessary for the understanding of the invention, and part of such apparatus is shown in central vertical section so that the construction throughout may be readily followed.

The ventilator-conduit A is enlarged at A¹ to receive an injector-conduit B. The upper end of the conduit A carries a double-acting valve, which is not shown because it forms no part *per se* of the present invention, of any convenient type which will permit the ingress of air when a lowering of 90

pressure takes place within the tank, and an egress of fluid when the pressure is raised within the tank. The valve-carrying portion lies outside of the tank or other container to which the apparatus is applied, but the lower portion, say from the flange indicated at A², lies within the tank. The part immediately below the flange A² contains one or more ports A³ which are situated well above the level of the fluid in the container, so that any gas generated can escape by these ports up through the conduit A and past the relief-valve at the top, or if the pressure is lowered within the container, the air may enter by the relief-valve at the top and pass into the container through the ports A³. Below the ports A³ the ventilating-conduit has an extension A⁴ which assists in the steaming hereinafter described, the bottom of this conduit preferably lying close to the bottom of the container.

The injector-conduit B has an elbow-bend B¹ so that connection can be made with it outside the conduit A by means of the external flange B² which is situated at a point where the injector-conduit enters the ventilator-conduit. On that face of the elbow which is toward the relief-valve, that is, toward the upper portion of the conduit A, is an opening B³ within which fits a valve C. The outer face of the valve is shaped to co-operate with a seating A⁵ formed on the interior of the conduit A, and the valve has a depending shroud C¹ which co-operates with the periphery of the aperture B³ to seal the said aperture when the valve is raised as hereinafter described. The exterior wall of the shroud C¹ is conical in form, the upper end being smaller than the lower end, and the lower portion is made thin for a purpose hereinafter described. The injector-conduit has an interior projecting portion C² within the elbow B¹ which provides a seating for the valve C when in the lowered position shown, and the valve further has an external lip C³ which may seat itself upon the exterior periphery of the opening B³ in the elbow. In the extension C², a guide-web C⁴ is provided to receive a stem C⁵ on the valve to steady the valve in its movements.

It will be observed that the injector-conduit B extends down well beyond the ports A³ in the ventilator-conduit A.

The operation of this apparatus is as follows:

So long as the valve C is in the position shown in the drawing, the relief-valve at the top of the ventilator-conduit, operates in the usual manner to maintain the pressure within the container approximately equal to that of the external atmosphere, but when the apparatus is to be used for cleaning purposes steam is admitted through the elbow B¹ of the injector-conduit B and the pressure of this steam immediately lifts the valve

C, which as will be seen constitutes a movable part of the wall of the injector-conduit. This movable part being raised, causes the outer surface, which is shaped as a valve, to co-operate with the seating A⁵ to shut off the relief-valve by shutting off the upper portion of the ventilator-conduit A. When in this raised position, steam is not allowed to escape by the opening B³ because the shroud C¹ keeps this sealed.

The shroud virtually constitutes a telescopic connection between the valve and the elbow B¹, but by making it conical as described, and thinning the lower edge, it is left free for up and down movement, and when in the raised position the thinned edge, which then beds against the inner face of the periphery of the aperture B³, is expanded by the pressure of steam to insure a fluid-tight joint between these parts. The steam is thus delivered from the lower end of the conduit B and being driven forward by the pressure with which it is introduced, there is little or no tendency to set up back pressure in the enlargement A¹ of the ventilator-conduit A to operate upon the lip of the valve C to thereby unseat it. The valve in fact is kept well up against its seating A⁵ by the pressure of the steam over a large area and only a small area is exposed for any back pressure which may exist in the said enlargement A¹. Further, the injector-conduit being carried below the ports A³ causes the steam delivered from it to draw in air or vapor through the apertures A³ and carry this down to the bottom of the conduit A⁴ where it is discharged with the steam at the bottom of the tank or container which is to be steamed. This arrangement insures a circulation being set up as fluid will always be drawn in through the apertures A³ which are at the top of the container and will be delivered at the bottom of the container.

Obviously the lower portion A⁴ may in some cases be dispensed with, but where it is desired to carry the steam direct down to the bottom of the container, it is necessary to provide the ventilator-conduit with this extension. As soon as the steam pressure is released within the container, the valve C drops back to the position shown in the drawing, so that the relief-valve can operate in the usual manner.

It will be understood that the use of the term "ventilator-conduit" throughout the appended claims, is intended to cover any conduit which is controlled by the double relief-valve for permitting ingress and egress of fluid, and the use of the term "injector-conduit" is intended to cover any conduit within the ventilator-conduit which discharges fluid along the conduit in the direction away from the valve.

For fire-extinguishing purposes, the ap-

paratus is used in the same manner as has already been described, that is to say, steam is admitted through the injector-conduit, but as the lower portion A⁴ of the ventilator-conduit is then immersed in the petrol or other fluid contained by the tank, the said steam or a great part of it will escape by the ports A³ into the upper part of the tank and will thus smother the flames; this is included under the general term—steaming—in the appended claiming-clauses.

What we claim as our invention and desire to secure by Letters Patent is:—

1. In apparatus for steaming and extinguishing fire within containers for liquids, the combination of a container, a ventilator-conduit having one end within the container and the other end projecting outside the same, a double-acting relief-valve for controlling the egress and ingress at the outer end of said conduit, a seating in said ventilator-conduit and an injector-conduit which enters a part of the ventilator-conduit controlled by the said relief-valve, has its delivery-end within the ventilator-conduit and directed away from the relief-valve, and has a movable wall-portion whose exterior is shaped to coöperate with said seating in the ventilator-conduit as a valve to shut off the said relief-valve when fluid under pressure is admitted to the injector-conduit, for the purpose set forth.

2. In apparatus for steaming and extinguishing fire within containers for liquids, the combination of a container, a ventilator-conduit having one end within the container and the other end projecting outside the same, a double-acting relief-valve for controlling the egress and ingress at the outer end of said conduit, a seating in said ventilator-conduit and an injector-conduit which enters a part of the ventilator-conduit controlled by the said relief-valve, has an elbow at the point where it enters the ventilator-conduit, the delivery-end of the elbow being directed away from the relief-valve, and has a movable wall-portion situated on that face of the elbow which is toward the relief-valve the exterior of which wall-portion is shaped to coöperate with said seating in the ventilator-conduit opposite such wall-portion so that the latter acts as a valve to shut off the said relief-valve when fluid under pressure is admitted to the injector-conduit, for the purpose set forth.

3. In apparatus for steaming and extinguishing fire within containers for liquids, the combination of a container, a ventilator-conduit having one end within the container and the other end projecting outside the same, a double-acting relief-valve for controlling the egress and ingress at the outer end of said conduit, a seating in said ventilator-conduit and an injector-conduit which enters a part of the ventilator-conduit con-

trolled by the said relief-valve, has its delivery-end within the ventilator-conduit and directed away from the relief-valve, and has a telescopic wall-portion whose exterior is shaped to coöperate with said seating in the ventilator-conduit as a valve to shut off the said relief-valve when fluid under pressure is admitted to the injector-conduit, the telescopic connection preventing the occurrence of any opening between the valve thus afforded and the injector-conduit, for the purpose set forth.

4. In apparatus for steaming and extinguishing fire within containers for liquids, the combination of a container, a ventilator-conduit having one end within the container and the other end projecting outside the same, a double-acting relief-valve for controlling the egress and ingress at the outer end of said conduit, a seating in said ventilator-conduit and an injector-conduit which enters a part of the ventilator-conduit controlled by the said relief-valve, has its delivery-end within the ventilator-conduit and directed away from the relief-valve, and has a movable wall-portion whose exterior is shaped to coöperate with said seating in the ventilator-conduit as a valve to shut off the said relief-valve when fluid under pressure is admitted to the injector-conduit, the said movable wall-portion having a shroud attached thereto which lies within an opening formed for it in the injector-conduit so that when the wall-portion is advanced by the pressure within the conduit the shroud seals the opening in which it moves as part of the said wall-portion, for the purpose set forth.

5. In apparatus for steaming and extinguishing fire within containers for liquids, the combination of a container, a ventilator-conduit having one end within the container and the other end projecting outside the same, a double-acting relief-valve for controlling the egress and ingress at the outer end of said conduit, a seating in said ventilator-conduit and an injector-conduit which enters a part of the ventilator-conduit controlled by the said relief-valve, has its delivery-end within the ventilator-conduit and directed away from the relief-valve, and has a movable wall-portion whose exterior is shaped to coöperate with said seating in the ventilator-conduit as a valve to shut off the said relief-valve when fluid under pressure is admitted to the injector-conduit, the said movable wall-portion having a shroud attached thereto which lies within an opening formed for it in the injector-conduit so that when the wall-portion is advanced by the pressure within the conduit the shroud seals the opening in which it moves as part of the said wall-portion, the operative portion of the shroud moreover being made sufficiently thin so

that it is automatically expanded against the sides of the opening in which it moves by the pressure within the injector-conduit, for the purpose set forth.

- 5 6. In apparatus for steaming and extinguishing fire within containers for liquids, the combination of a container, a ventilator-conduit having one end within the container and the other end projecting outside the
10 same, a double-acting relief-valve for controlling the egress and ingress at the outer end of said conduit, a seating in said ventilator-conduit and an injector-conduit which enters a part of the ventilator-conduit controlled by the said relief-valve, has its delivery-end within the ventilator-conduit and directed away from the relief valve, and has a movable wall-portion whose exterior is shaped to coöperate with
15 20 said seating in the ventilator-conduit as a valve to shut off the said relief-valve when

fluid under pressure is admitted to the injector-conduit, the said movable wall-portion having a shroud attached thereto which lies within an opening formed for it in the injector-conduit so that when the wall-portion is advanced by the pressure within the conduit the shroud seals the opening in which it moves as part of the said wall-portion, the operative portion of the shroud moreover being made sufficiently thin so that it is automatically expanded against the sides of the opening in which it moves by the pressure within the injector-conduit, the said shroud further having a conical exterior whereof the larger end is farthest from the valve-face of the movable wall-portion, for the purpose set forth.

In testimony whereof we have signed our names to this specification.

THOMAS ALBERT CROMPTON, JUNIOR.

FRANK CROMPTON.
